UNITED STATES PATENT OFFICE.

ANDREW P. HAWN, OF GOODLAND, INDIANA, ASSIGNOR, BY MESNE ASSIGNMENTS,
TO ADVANCE-RUMELY COMPANY, OF LAPORTE, INDIANA, A CORPORATION OF
INDIANA.

TRACTOR.

1,215,372.

Specification of Letters Patent. Patented Feb. 13, 1917.

Application filed July 9, 1914. Serial No. 849,878.

To all whom it may concern:

Be it known that I, ANDREW P. HAWN, a citizen of the United States, residing at Goodland, in the county of Newton and 5 State of Indiana, have invented a certain new and useful Improvement in Tractors, of which the following is a specification.

My invention relates generally to improvements in tractors and has for one object to provide a new and improved form 10 of light weight tractor. It is illustrated more or less diagrammatically in one form in the accompanying drawings, wherein—

Figure 1 is a plan view; 15 Fig. 2 is a side elevation of the left-hand side; Fig. 3 is an elevation of the right-hand side.

Like parts are indicated by the same letter throughout the several figures.

20 The main tractor frame is made up of the two parallel longitudinal frame members A¹, A² extending from end to end of the machine. They are tied together by the cross members A³, A⁴ which extend out beyond the frame to one side to meet and be attached to an inclined frame member A⁵, which, being curved at its forward end, extends across to tie together the frame members A¹, A² at the front of the machine. A⁶

30 is an inclined rear frame member attached at one end to the outer end of the frame member A⁵ extending rearwardly back to tie together the rear ends of the members A¹, A². A⁷ is a parallel frame member 35 forming a portion of the engine base and parallel with the members A¹, A². It is attached at either end to the members A⁵, A⁶ and intermediate its two ends to the members A³, A⁴. A⁸ is the drive wheel axle 40 mounted in bearings A⁹ on the frame members A¹, A², and A¹⁰ is the drive wheel provided with spikes A¹¹. A¹² is a bent fixed axle attached at one end to the frame member A⁷, supported adjacent its other end in the block A¹³ downwardly depending from the point of connection of the members A⁵, A⁶, and carrying an idler wheel A¹⁴. A¹⁵ is a stay member attached at one end to the frame member A adjacent its front end, 45

50 at the other end underslung by means of a stirrup A¹⁶ from the fixed axle A¹², and downwardly extended intermediate its two ends and braced by means of the brace A¹⁷ to the main frame. A¹⁸ is the forward steering wheel mounted in the fork A¹⁹,

which fork is supported in a bearing sleeve A²⁰, which sleeve is supported by the cross pieces A²¹ on the frame members A¹, A², the sleeve being supported by the braces A²², A²³, the load being applied on the fifth wheel 60 A²⁴ surrounding the fork and interposed between it and the frame and crosspieces A²¹. A²⁵ is a steering spindle supported on the frame members A¹, A² behind the steering wheel around which is wrapped 65 the steering cable A²⁶ which in turn is wound around a drum A²⁷. This steering spindle is controlled by means of a hand wheel A²⁸, the steering column A²⁹, pinion A³⁰ and gear A³¹. 70

B is an engine mounted in any suitable manner between the frame members A², A⁷, having a clutch B¹. B² is a clutch lever pivoted at one end on the frame A⁷ and attached to the clutch at B³. B⁴ is a control 75 lever pivoted on the frame member A¹ adjacent the hand of the operator. B⁵ is a connecting link leading from the lever B⁴ to a cross lever B⁶, which lever is pivoted on a bracket B⁷ between the frame members 80 A³, A⁴. B⁸ is a link interposed between the free end of the lever B⁶ and the clutch lever B² whereby the operator by manipulating the lever B⁴ may operate the clutch. B⁹ is a drive shaft, B¹⁰ a universal joint connecting it to the clutch B¹, and B¹¹ a driving pinion mounted on the end of the drive shaft B⁹. B¹² is a reverse shaft extending 85 transversely across the frame parallel with the axle of the driving wheel. Splined thereto are the two opposed miter gears B¹³, B¹⁴ free to slide and held against rotation. 90 These gears are provided with hubs adjacent stops on the frame members A², A⁷. B¹⁵ is the manually operated reversing lever. It is pivoted on the rear portion of the frame member A⁶. B²⁰ is a link connecting the downward end of the lever B¹⁹ with the rocker arm B²¹ on the rock shaft B²², which rock shaft is pivoted on the frame. B²³ is a lever mounted on the rock shaft B²², and B²⁴ is a link extending forwardly from said lever or arm B²³. B²⁵ is a rocker arm on a rock shaft B²⁶, 95 which rocker arm has pivoted to its end the link B²⁴. The rock shaft B²⁶ is rotatably mounted in the frame. It has mounted thereon the two rocker arms B²⁷, B²⁸. To one of these arms is attached a link B²⁹ having a loop B³⁰ to engage the shaft B¹². 100 105 110

2
To the other arm is attached a link B³¹ having on its end a loop B³² to engage the shaft B¹². The link and loop B³² has an enlargement B³³ at its far end inclined and projecting toward the miter gear hub, and the loop B³⁰ has a similar enlargement B³⁴ projecting similarly in the opposite direction toward the hub, so that when the rock shaft is rotated one link will be drawn from 10 and the other toward the shaft B¹², thus slipping the hub and miter gears back and forth as the case may be to engage either one or the other of the driving miter pinions to control the direction of rotation of 15 the reverse shaft B¹².

C is a sprocket mounted on the reverse shaft B¹². C¹ is a sprocket mounted on the countershaft C². C³ is a sprocket chain driving the countershaft from the reverse shaft. 20 C⁴ is a driving sprocket mounted on the counter-shaft, C⁵ a driving chain and C⁶ a bull or driving sprocket on the bull or driving wheel. Sprocket C⁴ is free to rotate on the shaft C². C⁷ is a clutch member keyed to 25 the shaft C² and having a lug C⁸ to engage a jaw C⁹ on the hub of the sprocket C⁴. C¹⁰ is a spring yieldingly throwing said clutch member into said jaw. C¹¹ is a bell crank control lever for said clutch, C¹² the control link and C¹³ a pedal control for the operator whereby this clutch may be disengaged to permit rotation of the engine and reversing mechanism without movement of the propeller wheel so that power can be 30 taken from the belt pulley C¹⁴ if need be.

It will be evident that, while I have shown in my drawings an operative device, still many changes might be made in size, shape and arrangement of parts without departing materially from the spirit of my invention. I wish, therefore, that my drawings be regarded as in a sense diagrammatic.

The use and operation of my invention are as follows:

45 When the machine is to be used for plowing, the plows will be arranged as shown, being attached at the center of the equalizing lever to the traction bar. The height of the front end of the plow beam will be adjusted 50 by means of the nuts on the suspending screws which may be moved up or down to raise or lower the front end of the plow beam. The two plows being attached one at either end of the equalizing lever, there is a 55 single point at which the tractive force of the engine is applied. This point, it will be noted in Fig. 1, is slightly to the right of the center of the driving wheel. This is necessitated by the fact that the outside plow 60 must be offset so that the weight of the tractor will not come too near the edge of the frame. This offset or eccentricity of the line of force will, of course, tend to swing the tractor to the right, and the idler wheel 65 on the left-hand side exerts a sufficient re-

tarding force to prevent this slight swing and makes this device easily steerable.

When the engine is started, the operator manipulates the reversing lever to throw one link or the other toward the reversing shaft and thus drive the forward moving or reversing gear into mesh with the constantly moving pinion and thus control the direction of rotation of this shaft. The operator will then throw in the clutch in the usual manner, and the machine will go ahead or reverse, as the case may be, being driven from the engine through the medium of the clutch, reversing gear, sprockets, countershaft and sprocket chains. When, however, 80 it is desired to take power from the belt without moving the engine forward, the operator will manipulate the clutch on the countershaft and disconnect the sprocket on the countershaft from driving connection 85 therewith so that the countershaft may rotate freely and power may be taken from the pulley on the reversing shaft.

When the tractor is under way with the plows in the downward position, plowing, of course, takes place. When the operator wishes to raise the plows he puts his foot on the plow raising lever and draws the clutch up against the spring to bring the friction clutch on the countershaft against the side of 90 the plow lifting drum and rotate it by its frictional drive. As this drum rotates it winds in the plow lifting cable and this results in a rocking of the plow lift rock shaft and the two plows are lifted out of the ground simultaneously. When they have 95 been lifted out a sufficient distance, the automatic catch comes into play and the operator by releasing the pressure of the friction clutch will allow the weight of the plows to 100 drop back upon this hook or catch and the plows will be held out of the ground. When it is desired to again bring the plows into operation he can either release this hook and let the plows drop violently or by manipulation of the plow lift raise the plows gradually, release the hook and allow them by gradually releasing the clutch to be gradually dropped into the ground.

When the machine is to be used for general traction purposes or hauling anything except plows, it is necessary only to withdraw the pivotal nut and bolt holding the equalizing bar and the traction bar. This releases the plows from traction and then 115 by disconnecting the chain from the plow lift the plows may be removed and the load applied to the traction bar in the usual manner, thus providing an all-purpose traction engine.

125 The steering of my tractor is, of course, carried out in the usual manner by means of the well known arrangement shown.

It will be noted that the arrangement of engine fly wheel and clutch with respect to 130

the body or frame of the machine is such that the center of gravity of the engine lies substantially on a line joining the axes of the driving and idler wheels and that the 5 engine is intermediate the driving and idler wheels so that in a sense my tractor operates somewhat similar to a motorcycle in that it has an idler wheel and a front steering wheel which carry substantially all the 10 load, the idler wheel carrying only a small portion of it. Experience shows that when the engine is in movement carrying a load the weight on the driving wheel is very materially increased and the weight on the 15 steering wheel and idler wheel is materially decreased so that with a light traction engine I am still able to get a maximum of load on a driving wheel where it is needed to give sufficient friction and adhesion for the necessary power. This result seems to be obtained by the off-set, by the particular arrangement of sprocket and driving chain and by the location of the engine and other heavy parts all in coöperation together with 20 the relation between the idler and driving wheel.

I claim:

1. A frame for tractors made up of two parallel frame members extending substantially the whole length of the frame, two inclined members tying the two ends of the longitudinal members together and intersecting at a point removed from them, a short longitudinal member parallel with 35 said main longitudinal members and supported on the inclined members, an engine mounted between said short member and one of the longer ones, a tractor wheel at one side of the engine, an idler wheel at the 40 other, said tractor wheel being interposed between the two parallel longitudinal frame members, and a steering wheel in front of and in line with the tractor wheel.

2. A tractor having a single drive wheel, 45 an idler wheel at one side thereof having its axis in the same vertical plane as the axis

of the driving wheel, a steering wheel in front of the driving wheel substantially in line with it and a draft connection at the rear end of the machine off-set a short distance beyond the center of the drive wheel away from the idler wheel, an engine supported between the driving and the idler wheel having its center of gravity substantially in the line between them, a power 55 transmission interposed between said engine and the drive wheel and arranged to exert an upward lift on the engine frame.

3. A tractor having a single drive wheel, 60 an idler wheel at one side thereof, a steering wheel in front of the driving wheel substantially in line with it and a draft connection at the rear end of the machine off-set a short distance beyond the center of the drive wheel away from the idler wheel, an engine supported between the driving and the idler wheel having its center of gravity substantially in the line between them, a power 65 transmission interposed between said engine and the drive wheel and arranged to exert 70 an upward lift on the engine frame.

4. A tractor having a single drive wheel, a steering wheel in front of and in line with the drive wheel, and a frame made up of two parallel side members, one on either side 75 of said wheels, said members being tied together by cross members, and being supported on the two wheels, an idler wheel at one side of the tractor member, diagonal frame members extending from the ends of 80 said two parallel side members converging toward the idler wheel, and a longitudinal member carried by them parallel with the two side members.

In testimony whereof, I affix my signature 85 in the presence of two witnesses this 25th day of June 1914.

ANDREW P. HAWN.
